UNITED STATES PATENT OFFICE.

CHARLES A. FRIEDRICH, OF BROOKLYN, NEW YORK.

SOCKET FOR VACUUM TUBES OR THE LIKE.

Application filed December 9, 1921. Serial No. 521,083.

To all whom it may concern:

Be it known that I, CHARLES A. FRIEDRICH, a citizen of the Republic of Germany, and a resident of Brooklyn, county of 5 Kings, and State of New York, have invented certain new and useful Improvements in Sockets for Vacuum Tubes or the like, of which the following is a specification.

10 The present invention relates to electric sockets particularly for vacuum tubes used in electric wireless apparatus.

Since the introduction of the three electrode vacuum tube into wireless apparatus 15 as receiving and transmitting device, it has been found that outside vibrations transmitted through the tube socket to the vacuum tube proper are very detrimental to the function of such vacuum tubes. These 20 sockets do not only communicate outside noises, but also shocks or jars felt by them through the structure in which the apparatus is used are transmitted to the vacuum tubes, as a result of which the different 25 electrodes are thrown into contact with each other, thereby disturbing their function and practically rendering the vacuum tube valueless.

Various devices have been constructed to 30 absorb such outside vibrations and shocks but most of such devices are too cumbersome and not sufficiently sensitive. Besides, such devices require too much valuable space in wireless apparatus.

35 In order to overcome these inconveniences, inefficiencies and drawbacks, I have constructed a novel vacuum tube socket which is equipped with means for absorbing outside vibrations, shocks, etc., and which is 40 adapted to occupy comparatively small space.

With this object in view, my invention consists in that contrary to the existing sockets in which contact with the prongs of the 45 vacuum tube is effected in an indirect way through the medium of plate springs or the like, my new socket is provided with shock absorbing direct contact producing means, which will support the tube so as to hold 50 it yieldingly and out of physical touch with the socket proper, and thereby rendering the socket very effective in the transmission and distribution of current through the different electrodes and preventing injury to or 55 disturbance of the functions of said electrodes through shock or outside vibrations.

My invention will be more fully understood by reference to the accompanying drawing in which similar reference characters denote corresponding parts, and in 60 which, Fig. 1 is an elevation of a vacuum tube equipped with my novel socket; Fig. 2 is an enlarged top plan view of the socket proper; Fig. 3 is an enlarged section on line 3-3 of Fig. 2; Fig. 4 is an enlarged 65 perspective view of a terminal arm carrying a coil forming part of my novel socket; Fig. 5 is a similar section to Fig. 3 of a part of the socket somewhat modified; Fig. 6 is a section on line 6-6 of Fig. 5; Fig. 70 Fig. 7 is a similar section to Fig. 5 of a further modification of the socket, and Fig. 8 is a section on line 8-8 of Fig. 7.

Referring to the drawing more in detail 75 a denotes the bulb ordinarily called the vacuum tube and generally used in wireless systems for receiving or sending purposes. In this tube P denotes the so-called plate made in form of a sleeve which encloses the grid G and filament F, the grid, filament 80 and plate being insulated from one another and conductively connected to the leads F', F'', G' and P', which pass through the insulation stem S and connect with wires W, leading to the contact pins or prongs C projecting from the metal frame or sleeve a' of the tube.

With the hitherto used construction electric connection between the electrodes of the 90 vacuum tube and the wireless system is brought about by means of a socket having the usual terminals for the attachment of the electric wires and contact pieces, usually plate springs, with which the prongs are 95 adapted to make indirect contact. Such socket forming part of the wireless apparatus is usually fixed to a stationary structure, wall, desk or the like. When the tube is engaged in such socket it forms with it a rigid piece, so that shocks or vibrations caused by outside 100 noises and communicated to the structure are transmitted to the tube as a result of which the different electrodes, the plate, grid and filaments, will be thrown into contact with one another, become injured rendering the tube valueless or will transmit outside 105 noises and disturb the transmission of messages or the like.

The socket 10 according to this invention, 110 comprises a disk of insulation material held low as at 10' and open at its bottom and which is formed in its top with a plurality of

perforations 10³. At its bottom the disk is formed with radial grooves 10² through which extend metal arms 11 forming the terminals for the electric wires (not shown). 5 These arms are held in position by screw bolts 12 fixed in the disk. There are as many perforations as there are prongs or pins C, thus in the present case four, and the same are arranged to register with and made 10 somewhat wider than the diameter of said prongs, so that the latter may freely pass through said perforations. Arranged in the hollow 10' of the disk are sockets 14 made according to the structure shown in Figs. 15 3 and 4 of coiled spring wire, such as copper. These sockets are suitably secured in upright position to the inner ends of the terminal arms 11 to extend close to the inner face of the top of the disk and to register 20 with the perforations 10³ therein. For fastening said coils in position to the arms 11 short screw bolts 13 are riveted or otherwise fixed to the latter and onto which the coils are threaded like nuts. The screw bolts will 25 engage only a few of the lower windings of the coils leaving the major portion of the latter flexible, so that the same may yield in different directions. The coils 14 are in diameter so admeasured as to snugly engage 30 around the prongs C passed through the perforations 10³ of the disk, and thereby not only hold the tube securely in position but also form an effective contact. A few 35 of the stop windings 14' of said coils are somewhat widened to facilitate the passage of the prongs into the coils. In length the coils are so admeasured that the prongs when engaged will not extend to the inner ends of the screw bolts 13, and owing to the 40 spring force of the coils, the tube will be held at an elevation from the upper face of the disk creating, a free space between the bottom of the metal sleeve a' and the disk sufficient to prevent physical contact 45 and thereby the transmission of shocks or vibrations from the socket to the tube.

Of course, instead of coils other shock absorbing means may be employed.

Thus according to Figs. 5 and 6 resilient or spring rods 15 may be fixed to the terminal arms at 15' and provided at their upper ends with split cup shaped members 16 serving to engage the prongs C. The mouth portion of said members may be widened to facilitate the passage of the prongs. By splitting the members longitudinally the latter will be made to fit various thicknesses of the prongs or to adapt themselves to irregularities thereof.

Another modification is shown in Figs. 7 and 8. There semicylindrical or trough shaped members 18 are hinged at 18' to resilient pins or rods 17 fixed to the arms 11 as at 17'.

By hinging the members 18 to the rods or

pins 17 and arranging them with their open faces opposite one another provision is made to prevent failure of effective contact between the prongs C and said members 18 by reason of irregular shapes or bends occurring in the prongs. 70

Owing to the flexible support of the contact members, such as the coils 14, the cups 16 or troughs 18 the engagement of the prongs C therewith will be insured even 75 though the latter may not be properly spaced due to some fault in the manufacture, or may have been accidentally bent.

The metal sleeve a' is usually provided with a pin or projection K. This pin is 80 utilized in the present construction of the socket to facilitate the positioning of the vacuum tube relative to the socket 10. On the upper face of the socket an arrow (see Fig. 2) is marked indicating the position 85 of the pin K when inserting the tube, so that the wires may be properly connected to the corresponding electrodes. The latter may be marked, as shown, on the disk opposite the terminals. 90

There may be other modifications made by those skilled in the art without departing from the principle of my invention. I, therefore, do not wish to restrict myself to the details shown and described. 95

What I claim and desire to secure by Letters Patent is:—

1. In a socket for a vacuum tube having projecting contact members, an insulation base, terminal members fixed to said body and universally yielding sockets conductively connected to said terminal members and adapted to engage said contact members, so as to support the vacuum tube out of physical contact with said base. 100 105

2. In a socket for vacuum tubes having contact prongs, a hollow insulation base having in one of its faces perforations for the free passage of said prongs, terminal members fixed to the opposite face of said base and projecting into the hollow thereof, and universally yielding sockets conductively connected to said terminal members and adapted to engage said prongs so as to support the vacuum tube at an elevation from 110 and out of physical contact with said base. 115

3. In a socket for a vacuum tube or the like having contact prongs, a hollow insulation base having perforations in one of its faces for the free passage of said prongs, terminal members fixed to the opposite face of said base and projecting into the hollow thereof and sockets of coiled flexible wire carried by said terminal members within the hollow of said base and capable of engaging said contact prongs, so as to support said vacuum tube at an elevation from and out of physical contact with said base for the purpose specified. 120 125

4. In a socket for a vacuum tube or the 130

like having contact prongs, the combination with an insulation base having contact terminals, of universally yielding sockets conductively connected to said terminals and 5 capable of engaging said prongs, so as to support said tube spaced apart from and out of physical contact with said base for the purpose specified.

5. In a socket for a vacuum tube or the 10 like having contact prongs, an insulation base having contact terminals, spring coils carried by said terminals and serving as

sockets for said prongs, said coils being enlarged at their free ends to facilitate the passage of said prongs and capable of frictionally engaging the latter, so as to support the tube at an elevation from and out of physical contact with said base. 15

Signed at New York, N. Y. this day of December, 1921.

CHARLES A. FRIEDRICH.
